[57] **CLAIM**

The ornamental design for a ladder hook bracket or the like, substantially as shown and described.

DESCRIPTION

FIG. 1 is a left side, top and front perspective view of a ladder hook bracket showing my new design;

FIGS. 2 and 3 are respectively front and rear elevational views thereof;

FIG. 4 is a left side elevational view thereof, the right side view being a mirror image;

FIG. 5 is a top plan view thereof; and

FIG. 6 is a right side, bottom and front side perspective view thereof.

FIG. 2.

FIG. 1.

FIG. 3.

FIG. 4.

FIG. 5.

FIG. 6.
